UNITED STATES PATENT OFFICE

2,316,158

ADJUSTABLE TOURNIQUET

Albert Eschner, Santa Monica, Calif.

Application May 20, 1942, Serial No. 443,755

6 Claims. (Cl. 128—327)

This invention relates to an adjustable tourniquet for arresting bleeding and circulation, and carries forward the purposes and objects of the tourniquet described and claimed in my co-pending application, Ser. No. 433,184; filed March 3, 1942.

Among the objects of the present invention are: To provide a tourniquet that may be more quickly applied to and removed from an injured limb, and which may also be more quickly, after being applied, adjusted to and from a momentarily relaxed condition to prevent an injurious stasis of the circulation throughout the injured part; to dispense with the necessity of using a separate part or additional extension to function as a pressure pad; to provide for a quicker and more convenient adjustment of the device for properly fitting around limbs differing greatly in size; to provide a more compact structure no part of which will protrude in an objectionable manner from a limb to which the device is applied; to provide an improved combination of cooperating gripping elements; and to simplify construction and further reduce the cost of manufacture of devices of the kind to which the invention pertains.

A further and more specific object of the invention is to provide an improved combination of an elastic band to encircle the injured limb, with a swingable lever which serves both to tighten said band and to apply an efficient radially directed pressure to the tissue overlying the bleeding blood vessel.

Another object of the invention is to provide a device particularly well adapted for quick application to a snake-bitten limb to prevent the injected poison from passing into the general circulation.

Other objects, advantages and features of invention will hereinafter appear.

Referring to the accompanying drawing, which illustrates what is at present deemed to be a preferred embodiment of the invention:

Fig. 1 is a plan view of the device showing it in the extended condition, portions of the flexible connection being broken out in order to contract the length of the view. Also one of the clips is partly sectioned.

Fig. 2 is a side elevation of the device illustrating the position thereof after the first step in applying it to a limb has been taken, the limb being shown in cross section.

Fig. 3 illustrates the same structures as Fig. 2 and differs therefrom only in that the device is shown in the fully applied condition.

Referring in detail to the drawing, the flexible connection or band 10 for encircling one or more times the injured limb 11 should possess considerable elasticity in order to hold more firmly in place the part of the tourniquet which applies pressure to the injured blood vessel. Said band has a folded over end portion 12 which is passed through the slotted basal portion 13 of a rectangular sheet metal clip 14, the two runs of this folded over part of the connection being shown vulcanized together in a flatwise manner, but they may be secured to each other by a grummet or in some other conventional manner. Said clip 14, at its free end, is contracted in a symmetrical manner as to its width, thus forming an extension 15 which terminates in a hook 16. This hook is designed to engage an elongated compressor member or clip 17 in the manner shown in Fig. 3, when the device is in the fully applied condition.

Said clip 17 has a body portion 18 and end portions 19 and 20 both of which are deflected toward the same face of the clip of which they form a part thereby giving said clip a longitudinally dished appearance.

The end portion 19 of the clip 17 is formed of a hook shape, the hook having a terminal portion 21 which substantially parallels the opposite side portion 22 of the hook of which it forms a part. These opposed, parallel, spaced apart portions 21 and 22 are respectively provided with adjacent, spaced apart slots 23 and 24 that are parallel to each other and thus afford means for feeding the strap 10 through the hook portion 19 of the clip 17. The open side of the laterally deflected hook portion 19 of the elongated compressor member 17 is directed toward the plane in which the body portion of said compressor member lies, and the adjacent slots 23 and 24 afford means of swingably connecting said compressor member with the elastic strap 10.

The end portion 20 of the compressor clip 17, which is opposite to its hook 19, is furnished with a spacious, rectangular opening 25 adjacent to its free end, thus affording an anchor bar 26 over which the hook 16 of the clip 14 hooks when the compressor clip 17 is in the applied position shown in Fig. 3.

In Figs. 2 and 3 a blood vessel 31 is shown located between a bone 30 and that side of the limb to which the compressor plate 17 is applied, said blood vessel being shown collapsed in Fig. 3 owing to the pressure of the applied device to the overlying tissue.

The slots 23 and 24 of the hooked-shaped part of the compressor member form passages for the band 10, are each sufficiently long to prevent the edges of said band from binding against their ends, and are each of a width only slightly greater than the thickness of said band. Hence said clip can be slid freely along the band only when the body portion of the compressor clip extends approximately parallel to the adjacent part of the band, as shown in Fig. 2.

In using the device to check hemorrhage, after the elastic band 10 has been wound around the injured limb till portions of said band come opposite to each other as shown in Fig. 2, the compressor member 17 being at this time in its inoperative, unsprung position and therefore freely slideable along the band; said compressor member is then slid along the band as may necessitate to position it adjacent to the blood vessel to be compressed, and thereupon said compressor member is swung over and down to the applied position shown in Fig. 3 where it compresses the blood vessel 31, whereupon the hook 16 is applied to the anchor bar 26 of the compressor member, thereby to maintain said member in its operative position. The down swinging of said compressor member forms a kink in the band shaped as a closed loop, as shown in Fig. 3, thus producing increased tension in the kinked and adjacent part of the band. If the band has been properly adjusted around the limb before the hook 16 is applied, the end portion of the band that carries the hook will also necessarily be stretched in bringing the hook into engagement with the bar 26 to which it is applied. This double tensioning of the band adds to the efficiency of the device when used as a tourniquet and is a particularly valuable asset when the device is used to obstruct circulation to prevent poison injected from the bite of a venomous animal from entering the general circulation. In applying the compressor member in the manner which has been stated, said member is swung through an angle of 180 degrees and after the hook 16 has been applied thereto it produces an efficient, radially directed pressure directly over the blood vessel to be compressed, which pressure is rendered more efficient by reason of the dish-shaped character of said member. However, the firm pressure of the metal clip of which said member consists will not irritate the underlying tissue, because at least a single run of the elastic band will overlie that part of the tissue which is subjected to the greatest amount of pressure. The frictional engagement of the applied clip 17 with the part of the band 10 underlying it, in conjunction with the grip of the slotted part of said clip upon the band at the same time, positively prevents displacement of said clip.

It should be understood that the present disclosure is for the purpose of illustration only and that this invention includes all modifications and equivalents which fall within the scope of the subject matter claimed.

What is claimed is:

1. A tourniquet consisting of a flexible strap for passing around a bleeding limb, an elongated compressor member having at each end a laterally deflected portion, said deflected portions being located at the same side of said compressor member and a body portion uniting said end portions, there being a pair of adjacent par-

allel slots leading through one of said end portions of said clip, said strap extending through said slots and thereby swingably connecting said member to it, the opposite end portion of said member having an anchor portion to receive a hook when said member is swung about its connection with said strap as an axis through an angle of 180 degrees from an inoperative to an operative position, and a hook attached to one of the end portions of said strap to cooperate with said anchor portion when said member is in its operative position.

2. The subject matter of claim 1 and, the slotted part of said member consisting of a hook the open side of which is directed toward the plane occupied by the body portion of said member.

3. A tourniquet comprising a flexible strap for passing around a bleeding limb, a compressor member consisting of an elongated plate dish-shaped in the direction of its length, and having a laterally deflected end portion which includes two runs in an adjacent parallel relation to each other, each of said runs being slotted so that said strap extends through them both, thereby swingably connecting said member with said strap, the opposite end portion of said clip having an anchor portion to receive a hook, and a hook attached to one of the end portions of said strap to cooperate with said anchor when said compressor member is in its operative position with the bottom face of its dish-shaped portion in exterior contact with said strap when the latter is applied to the limb of a human subject.

4. The subject matter of claim 3 and, said compressor member, when moved toward its operative position to the limit of its swinging movement, producing an outwardly directed tensioning loop in the aforesaid strap.

5. In a device of the kind described, an elastic strap to encircle a limb of a human subject, a hook carried by one end portion of said strap, a compressor member consisting of an elongated plate of rigid sheet material which has a presser portion and at each end of said presser portion a laterally deflected portion, said deflected portions being located at the same side of said compressor member, one of said deflected portions including two adjacent spaced apart runs each of which has through it a slot opposite to the slot of the other, said elastic strap extending through both of said slots in a freely slideable manner when said compressor member is in its inoperative position, said member being swingable from such position to an operative position wherein the face thereof farthest from its said projecting portions presses exteriorly against said strap when the latter is in its applied position in relation to the limb of a human subject, said compressor member having an anchor portion at the end thereof opposite to its aforesaid two slots, said hook being engageable with said anchor portion to hold said compressor member in its said operative position.

6. The subject matter of claim 5 and, said compressor member when swung from its inoperative to its operative position moving through an angle of substantially 180 degrees and kinking into a closed loop the part of said strap which passes through its said two slots, thereby adding to force with which said strap grips the limb to which it is applied.

ALBERT ESCHNER.
